(57) **CLAIM**

The ornamental design for a wound closure device, as shown and described.

DESCRIPTION

FIG. 1 is a front view of a wound closure device showing our new design.

FIG. 2 is a back view of the wound closure device of FIG. 1.

FIG. 3 is a top view of the wound closure device of FIG. 1.

FIG. 4 is a bottom view of the wound closure device of FIG. 1.

FIG. 5 is a right side view of the wound closure device of FIG. 1; and,

FIG. 6 is a left side view of the wound closure device of FIG. 1.

The dashed lines show surface ornamentation and portions of the wound closure device that form no part of the claimed design. The grids of dashed lines show semi-transparent mesh portions that sit on a top surface of the wound closure device that form no part of the claimed design. The dash-dot-dash lines show unclaimed boundary lines of the claimed design.

1 Claim, 3 Drawing Sheets
